UNITED STATES PATENT OFFICE.

FRANK ADAM SHUNK, OF STREATOR, ILLINOIS.

GLASS-MOLD-OPERATING MACHINE.

SPECIFICATION forming part of Letters Patent No. 678,287, dated July 9, 1901.

Application filed March 30, 1901. Serial No. 53,619. (No model.)

To all whom it may concern:

Be it known that I, FRANK ADAM SHUNK, of Streator, in the county of LaSalle and State of Illinois, have invented a new and useful Improvement in Glass-Mold-Operating Machines, of which the following is a specification.

My invention is in the nature of a labor-saving machine designed to open a mold in which a bottle or other object has been made, to remove the bottle therefrom, then close one side of the mold, then place the bottle on a stand made to receive it, and then, after material for a fresh bottle has been placed in the mold, to close the other side of the mold, which has been left open preparatory to blowing another bottle.

My invention is designed to provide means whereby most of these operations can be quickly and successively performed in a practically automatic manner, which I will now proceed to fully describe with reference to the drawings, in which—

Figure 1 is a side elevation of the machine. Fig. 2 is a plan view with the mold closed and the bottle removed to its stand. Fig. 3 is a plan view with the mold open and the bottle about to be removed. Fig. 4 is an end elevation from the left-hand side of Fig. 1. Fig. 5 is a vertical section through the mold and its subjacent plates. Fig. 6 is a perspective view showing the internesting faces of the plates below the mold. Fig. 7 is an underneath view of a portion of the table. Fig. 8 is a perspective view of the driving-gears and clutch mechanism. Fig. 9 is a horizontal section through the bottle-carrying post. Fig. 10 is a section of the same on line 10 10 of Fig. 9. Fig. 11 is a vertical section through the bottle-carrying post.

In the drawings, A represents an elevated platform upon which the glass-blower stands, and in which platform are arranged two treadles T and T', Figs. 1 and 4, connecting with mechanism below, and one of which serves to close the mold and the other to start the machine into automatic action.

S represents the stand or table surface of my machine, which is supported upon legs 50 suitably braced, as shown. This stand occupies a lower position than the platform A, so as to bring the mold into proper relation

to the glass-blower. M is the mold, and B is the bottle, which in Fig. 1 has been transferred by the machine to its place of deposit. 55

The purpose of my machine is to automatically open the mold M, seize the hot bottle B, Fig. 3, and transfer it to the position shown at B, Fig. 1, and close the mold again, the operation being under the control of the workman through the agency of the treadles T T'.

I will now proceed to describe in detail the construction of parts and the successive operations by which this result is attained.

C is the main drive-pulley, which receives 65 motion from a driving-belt connected with any suitable source or power. This pulley is rigidly fixed to a short horizontal shaft C', Fig. 8, journaled in the framework, and which shaft bears a rigidly-attached gear-wheel C², 70 with two laterally-projecting pins c c.

D² is a larger gear-wheel arranged in the same plane with C², to be engaged thereby, but having at a point d no teeth on its periphery. When this point d is opposite the 75 gear C², the gear D² is out of mesh and is not rotated. The gear-wheel D² is rigidly fixed to a short horizontal shaft D', having on its inner end a crank D, by which motion is transmitted to the working parts of the machine at the required intervals. The pulley C, shaft C', and gear C² are driven continuously, and the gear D² is connected thereto at intervals at the will of the operator, as follows: To the side of gear D² there is jointed 80 a clutch-arm d', so as to work in a plane at right angles to that of the gear. This clutch-arm is normally held out of range of contact of the pins c on gear C² by a spring d', but is adapted to be engaged therewith by being 85 thrown into their plane of action by one of the treadles. When so thrown in, one of the pins c turns the clutch-arm d' and also the gear D² far enough to cause the blank space d in its periphery to pass beyond the wheel 90 C² and allow the teeth of D² to engage those of C² and be turned thereby through a complete revolution until the blank space d comes opposite the wheel C² again, when the wheel 95 D² and the automatic mechanism of the machine stops again. To throw the clutch-arm 100 d' into engagement with the pins c at the will of the operator, the upturned end e of a horizontal lever E bears against it and forces it

in whenever lever E is deflected. This lever is fulcrumed in the framework to play in a horizontal plane, and its outer end is jointed to a vertical lever E', Figs. 8 and 4, fulcrumed 5 to the bottom of the platform A, and a horizontal connecting-rod E² extends from said lever E' to the downwardly-projecting end of a T-shaped lever E³, which is fulcrumed at its center to hangers from the platform. One 10 horizontal arm of this lever is connected by a vertical push-rod E⁴ to the treadle T above the platform, and the other horizontal arm is provided with a weight E⁵, which normally holds the treadle up and the end e of the lever E away from the clutch-arm d'. When, 15 however, the operator desires to start the machine into automatic action, a pressure of his foot upon the treadle T throws the end e of lever E against the clutch-arm d' and by 20 forcing the latter against its spring and into range of the pins c on gear C² causes D² to be turned initially thereby until the teeth of D² become engaged by those of C² to continue the revolution.

25 The mold M (see Figs. 3 and 5) consists of two half-sections hinged on one side and provided on the other with horizontally-projecting yoke-arms m m', the yokes of which are of different length. The yokes consist of a 30 radial arm having a three-sided loop or keeper which is adjustable lengthwise the arm by means of set-screws s. In these yokes rest friction-rollers n n' on the upper ends of vertical stems n² n³, attached to crank-arms N 35 N', which swing about the centers o o', and have short shaft extensions that pass through the table and are acted upon by mechanism beneath the table to open or close the said arms N N'. When these arms swing to the open position, (see Fig. 3,) their ends bearing the rollers n n' act upon the yokes m m' and open the two hinged sections of the mold. The mold M rests upon a bottom plate M', which has a 40 raised and undercut seat m², around which the two halves of the mold are closed and which forms the base for the bottom of the bottle. The bottom plate M' has (see Figs. 5 and 6) on its under side lugs m³, and to it I apply a plate with an oblong recess m⁴, which 45 fits upon a correspondingly-raised oblong projection m⁵, formed on the top of an adjustable plate M². This plate is made vertically adjustable to suit the height of the bottle or other article by means of four screw-stems m⁶, which are tapped through threaded holes in each corner of the plate and have reduced lower ends that are seated in and turn in four holes in the table S. By turning these screw-stems the adjustable plate M² is 50 raised or lowered to bring the mold into proper position for the arms N N' to open and close the molds.

I will now describe the devices for taking the bottle out of the mold. In middle position between the arms N N' and extending longitudinally of the table there is a slot (see Figs. 2, 3, 7, and 9) in which slides a cross-

head O. On the upper side of the table, along one side of the slot, is fixed a rack-bar O', having at each end an upright straight flange O². 70 In the cross-head is mounted a tubular post P, adapted to rotate about a vertical axis and bearing on its lower end a segmental gear p, Figs. 9 and 11, adapted to engage with the rack and to rotate the tubular post a semi-revolution as it moves back and forth. Just above the segmental gear and rigidly attached to the tubular post is a square projection p', adapted to strike against the flanges O², Figs. 2, 3, and 11, which act as guides and 75 stops to limit the rotation of the tubular post and to hold the lifting-arm R, which it carries, to an exact stopping-point in relation to its rotary swing. As this arm R carries the pincers R', which seize and transfer the bottle from the mold to the stand on the opposite side, the necessity for stopping this arm in an exactly opposite radial position will be apparent. The lifting-arm R, Figs. 1 and 11, is rigidly fixed to a vertical stem R², which 80 extends down through the tubular post P and is acted upon by devices below the table to raise and lower it to give a lifting action to the arm to lift the bottle after it has seized it in the mold, instead of dragging it 85 off laterally. The pincers R' on the arm R consist of two spring-arms r r, playing in a loop r' on the end of the arm and embraced along their shank portions by a second loop r² on the end of a rod r³, fixed to the top of 90 the vertical lever r⁴. This lever is fulcrumed at r⁵ to the tubular post, and its upper end is slotted, and through this slot passes the lifting-arm R, so as to cause the lifting-arm to 95 partake of the rotary motion of the tubular post and also to allow the lifting-arm to have a rising-and-falling movement at the moment of picking up and depositing the bottle. When the lifting-arm is turned inwardly to the machine, its pincers occupy a position 100 in the center of the mold, as in Fig. 3, so as to grab the neck of the bottle, and when the lifting-arm is turned outwardly from the machine said pincers are directly over a stand V, which receives the bottle. This stand is 105 flanged and contains an asbestos mat and is carried on the top of a stem V', which by a set-screw v is held in a socket v' on a projecting arm V² from the machine. By means of the set-screw v the stand V may be raised or 110 lowered to suit the height of the bottle or other object being molded.

In order to open and close the pincers about the neck of the bottle, each spring-jaw of the pincers is formed with a swell r⁶, Figs. 125 2 and 3, and when the loop r² is forced over this swell the spring-jaws are forced together to clamp the bottle-neck in seizing the same, and when said loop r² is drawn back from said swell the spring-jaws separate to drop the 130 bottle on the stand V. To give this motion to the loop at the proper time in an automatic way, there is at the inner end of the slot in the table a stationary post U, Figs. 1 and 2,

with an abutting arm u , which when the lifting-arm enters the mold comes against the lower end of lever r^4 , as in dotted lines, Fig. 1, and pushes the loop r^2 over the swell 5 on the spring-jaws, causing them to grip the bottle-neck, as in Fig. 3. On the outer end of the table there is a corresponding post U' , which rises to a higher position than U and has its end bent inwardly, so as to strike the lever r^4 above its fulcrum just at the moment that said lifting-arm is above the stand V . This contact against lever r^4 forces back the loop r^2 away from the swell on the spring-jaws 10 of the pincers and allows the latter to expand to drop the bottle on stand V . The rotary movement of the lifting-arm through a half-revolution is given by the segmental gear p engaging with the rack O' , and the stopping of the lifting-arm in true alinement is effected 15 by the square projection p' against the flanges O^3 . The backward-and-forward movement of the cross-head and its lifting-arm in the slot in the table which carries out the aforementioned movements is effected (see Figs. 1 and 25 7) by a pitman W under the table, one end of which pitman is secured to the crank D and the other end is jointed to the bottom of the cross-head and is made with a projecting cam w , which cam, when the lifting-arm and 30 its vertical rod is in the inner position, comes against the lower end of the vertically-sliding rod R^2 of the lifting-arm and gives the lift to raise the bottle slightly in the mold just before transferring it by the lateral swing to the 35 stand on the other side.

To open and close the mold, (see Fig. 7,) the axes of the crank-arms $N N'$ have attached to them below the table rigid tappet-arms $t t'$, which are connected by pitmen $t^2 t^3$ to cranks 40 $t^4 t^5$ on a rock-shaft T^2 , which has another arm T^3 , that supports a weighted vertical rod T^4 , that connects with the treadle T' above the platform A . The weight on rod T^4 is to aid in opening the heavy mold. The two arms 45 $N N'$, which open and close the mold-sections, are acted upon automatically to open the mold (see Figs. 7 and 1) by two pins $x x'$ on the lower side of the reciprocating cross-head, which pins come in contact with the tappet-arms $t t'$ and work the arms $N N'$. When 50 the pins $x x'$ operate upon the tappets $t t'$ on the inward movement of the cross-head, they open the arms $N N'$ and also the two sections of the mold, and when the cross-head moves back the two-pronged or double-acting tappet 55 t' is acted upon to close one section of the mold, the other one being left open until the glass-blower puts the material for a new bottle in it. He then, at will, by pressing down 60 treadle T' , rocks the shaft T^2 and through connecting-rod t^2 and tappet t closes the other section of the mold. To permit this independent action, the connection of pitman t^3 to the other tappet t' is made by a slotted and 65 sliding joint j .

The operation of my machine is as follows: Assuming the pincers to be in their outermost

position above the stand made to receive the bottle and the gear-wheels to be out of mesh, the operator presses with his foot upon treadle T' and engages the gears. The pincers now swing around and with the cross-head move toward the mold, rotary motion being imparted to the pincers by the segmental gear and rack. As the cross-head moves toward the mold the pins on the lower side of the cross-head act upon the tappets $t t'$ and open the two sides of the mold. The pincers then, being held in alinement by the square projection and the flange on the table, enter the mold 80 and seize the bottle by the neck, the stationary abutment-arm acting upon the lower end of the pincer-lever to cause the pincers to close upon the bottle-neck. The lifting-arm now rises slightly to lift the bottle by the engagement of the cam on the lever below the table with the lower end of the lifting-rod. Then as the cross-head returns to its outermost position the rack by the side of the table-slot turns the segmental gear and rotary 85 post, swinging the pincers around to a diametrically opposite position, the square projection on the post and the upright flange at the outer end of the slot causing the lifting-arm, with the bottle, to stop immediately over the stand which receives the bottle. The pincer-lever now strikes the outer abutment-arm at a point above its fulcrum, which opens the pincers and drops the bottle on the stand. As the cross-head moves back it closes one 90 half of the mold, and after the operator has inserted the glass for a new bottle into the mold he closes the other half of the mold by pressing with his foot on the treadle T' .

Having thus described my invention, what 105 I claim as new, and desire to secure by Letters Patent, is—

1. In a machine of the kind described, a mold made in two hinged sections having radially-projecting handle-arms, yokes fixed 110 upon the arms, and vertical stems playing in said yokes and mounted upon radially-swinging arms to open and close the mold as described.

2. In a machine of the kind described the 115 combination with the mold-section hinged as described of a base-plate having on its upper side an elevated seat for the molded object, a supporting-table, and an adjustable plate interposed between the table-surface 120 and the base-plate of the mold, and having tapped in the same vertical supporting and adjusting screws to raise or lower said adjustable plate to suit the height of the object being molded substantially as described. 125

3. In a machine of the kind described, a mold having hinged sections, an imperforate base-plate having a raised projection on its upper side forming the bottom of the mold, and a subjacent supporting-plate for the base-plate, said supporting-plate and base-plate 130 being formed with an oblong internesting projection and recess to prevent accidental displacement when in action and yet permit

ready detachability substantially as described.

4. In a machine of the kind described, the combination with a mold made in two hinged sections; of an imperforate base-plate having on its surface a raised projection forming the bottom of the mold, a subjacent supporting-plate for the base-plate, said supporting-plate and base-plate being formed with an internesting projection and recess, a table-surface for the supporting-plate, and set-screws adjustably connecting the table-surface to the supporting-plate substantially as and for the purpose described.
- 15 5. In a machine of the kind described, the combination with a sectional mold and a support located at a distance for receiving the molded article; of a rotary-adjustable and rectilinearly-traveling arm with pincers arranged to vibrate between the mold and said support and to take the object from the mold and transfer it to the support substantially as described.
- 25 6. In a machine of the kind described, the combination with a sectional mold having opening yokes, and a support located at a distance for receiving the molded article; of oscillating arms entering the yokes for opening and closing the mold-sections, and a rotary-adjustable and rectilinearly-traveling arm with pincers arranged to vibrate between the mold and the said support and to take the object and transfer it to the said support substantially as described.
- 35 7. In a machine of the kind described the means for opening the mold consisting of two horizontally-projecting yoke-arms, a table-surface, horizontally-oscillating arms above the table with vertical ends entering said yokes, tappets attached to the axes of said arms below the table, and a reciprocating cross-head with pins acting upon said tappets substantially as described.
- 45 8. In a machine of the kind described, the combination with the sectional mold each hinged section of which has a radially-projecting arm and yoke; of automatic means for opening both sections of the mold and closing one section consisting of swinging crank-arms with stems entering the yokes, tappet-arms attached to the lower ends of the axis of the swinging arms, and a reciprocating cross-head acting upon the tappet-arms, and supplemental means for finally closing the other section of the mold said supplemental means being independent of the automatic means and under the control of the workman substantially as described.
- 55 9. In a machine of the kind described, the combination of a slotted table, a mold made in hinged sections with projecting yokes, two horizontally-oscillating arms bearing vertical stems entering the yokes, two tappets connected to said arms and arranged below the table, a reciprocating cross-head with pins acting upon the tappets, a rock-

shaft with crank-arms and pitmen connecting with said tappets, one of said tappets being made double-acting and having a slotted connection with its pitman, and means for operating said rock-shaft at will to make the final closure of the mold as described.

10. In a machine of the kind described, the means for reversing and stopping in alignment the lifting and carrying arm, comprising a slotted table having on one side of the slot a rack with a straight guide at each end of it, a reciprocating cross-head arranged in said slot and bearing a vertical post having a segment-gear engaging with the rack, and flat bearings engaging with the straight guides at the ends of the rack, substantially as described.

11. In a machine of the kind described, the combination with a reciprocating cross-head carrying a post with means for rotating it through a half a revolution; of a horizontal lifting and carrying arm bearing two spring-jaws forming pincers, having swelled portions, a loop embracing these jaws, a vertical lever attached to this loop and fulcrumed on the post, and two stationary abutments arranged at the ends of the travel of the cross-head and arranged to contact with the lever on different sides of its fulcrum to close and open the pincer-jaws substantially as described.

12. In a machine of the kind described, the combination with the mold, and a reciprocating and rotary turning hollow post; of a vertical rod sliding in said hollow post and having a horizontal carrying-arm, a sliding cross-head carrying said post and rod, and means for reciprocating the cross-head and lifting the rod and its carrying-arm at the moment of seizing the object to be removed from the mold substantially as described.

13. In a machine of the kind described, the combination with the mold and a reciprocating and rotary turning hollow post; of a vertical rod sliding in said hollow post and having a horizontal carrying-arm, a sliding cross-head carrying said post and rod, a pitman jointed to said cross-head and having a cam-head arranged to lift the said rod, and driving mechanism for the pitman substantially as described.

14. In a machine of the kind described, the combination with the mold, the receiving-stand, and automatic mechanism for transferring the object from the mold to the receiving-stand; of an automatic driving-gear arranged to be set into action by the workman and consisting of a constantly-rotating driving-gear with a laterally-projecting pin, a driven gear-wheel arranged in the same plane with the driving-gear and having a blank space in its circle of teeth, a spring-actuated clutch-arm jointed to the driven gear and extending to the pin of the other gear, and a lever and treadle mechanism for throwing the clutch-arm into range of engagement of the

pin to give the start to the driven gear and bring about the meshing of its teeth with those of the driving-gear substantially as described.

15. In a machine of the kind described, the combination with a table having a sectional mold and automatic means for opening the mold and transferring the molded object, and closing one half of the mold, means for independently closing the other half of the mold, 10 an elevated platform bearing two treadles,

one of them connecting with the automatic mechanism for starting its action, and the other connecting with the means for finally closing the mold at the will of the operator substantially as described.
